CLAIM

The ornamental design for a wine key, as shown and described.

DESCRIPTION

FIG. 1 depicts a rear plan view of a wine key showing the claimed design;

FIG. 2 depicts a first side plan view thereof;

FIG. 3 depicts a front plan view thereof;

FIG. 4 depicts a second side plan view thereof;

FIG. 5 depicts a top end elevation view thereof;

FIG. 6 depicts a bottom end elevation view thereof;

FIG. 7 depicts a first side perspective view thereof in a closed configuration; and,

FIG. 8 depicts a first side perspective view thereof in an open configuration.

The claimed ornamental design for a wine key article of manufacture preferably may be used for purposes of opening a beverage bottle having a stopper, such as a cork, opening a bottle having a pry-off closure, such as a crown cork-type metallic bottle cap, and cutting a seal around a neck of a beverage bottle, such as a foil seal.

1 Claim, 5 Drawing Sheets
